UNITED STATES PATENT OFFICE.

HARLAN S. ROBINSON, OF ALBANY, NEW YORK.

FUSE-HANDLING DEVICE.

Application filed March 23, 1925. Serial No. 17,658.

My invention relates to fuse-handling devices, and particularly to devices of this character for use in removing and replacing fuses in potential transformers without 5 "killing" the line for that purpose.

One of the objects of my invention is to provide a device of this character which will grasp the fuse securely with no danger to the operator who may stand at a considerable 10 distance from the transformer. Another object of my invention is to provide a device of this character which may be locked in positive engagement with the fuse so that the operator may use both hands for manipulating the device in removing the fuse. Another object, is to provide a device which may be easily adjusted to accommodate fuses of different size. And still another object is to provide a device of an extremely simple 15 character, which will be absolutely reliable, and which may be cheaply and easily constructed.

With these objects in view my invention consists in the novel elements and the arrangements and combinations thereof which are illustrated in the accompanying drawings in which—

Fig. 1 is a general side elevation of my device showing its application to a fuse, and 20 in which a portion of the handle is broken away for the purpose of showing how the device is adjusted for different size fuses;

Fig. 2 is a fragmentary view of the transformer, with a fuse therein, looking from 25 the side toward the operator;

Fig. 3 is a fragmentary plan view of my device;

Fig. 4 is a perspective view of the fuse grasping mechanism; and

Fig. 5 is a section on the line 5—5 of Fig. 3.

Referring to the drawings, my device, in its preferred form, comprises an angular block of hard wood or other insulating material 1, which is somewhat shorter than the fuse to be handled, and which is slightly concaved on the lower side, as shown at 23, to fit the contour of fuse 2. Fitted upon the extremity of the block 1 is a tube 3 of fiber or other rigid insulating material which is secured to the block 1 by means of screws 4. The tube 3 may be of any suitable length. Slidably fitted in the other end of the tube is the handle 5. Pivotally connected to the block 1, at 6 and 7, are the spaced hooks 8 and 9, respectively. These hooks are also

connected together by the link 10, so that they move together in parallel relation. The hook 9 is bent at an angle A, which may be somewhat greater than 90 degrees. The upper part 11 of the hook is bent 180 degrees so that the portion 12 is separated from the portion 13 a distance substantially equal to one-half of the thickness of the block 1. The top of the block 1 is mortised to receive the portion 12 of hook 9, which extends into the block to a point slightly beyond the axis of the tube 3. Attached to the extremity of the portion 12 is the clevis 14, which is threaded to receive the fiber rod 15 secured 60 therein by means of the set-screw 16. The fiber rod 15 is substantially in the axis of the tube 3 and extends to a point near the open end of that tube where it is threaded into a sleeve 24, and secured therein by means of 65 the set-screw 17. Threaded into the other end of the sleeve 16 is the metal screw 18, which extends axially through the handle 5. Interposed between the threaded sleeve 16 and the inner end of the handle 5 is the 70 spiral spring 19, which is sufficiently strong to prevent the handle 5 from sliding along the screw 18, when it is pushed into the tube 3 to release the fuse from the hooks. Inserted in the handle 5 is the screw 25, which 75 passes through the angular slot 20 in the tube 3.

The operation of my device is as follows: The hooks 8 and 9 are slipped under the fuse 2, when the parts are in the position 80 shown by the solid lines in Fig. 1, and the block 1 is allowed to rest upon the top of the fuse. The handle 5 is then drawn out to the position 5'. The pull on the handle is transmitted through the screw 18, the sleeve 24, 95 the rod 15, and the clevis 14, to the hook 9, which is drawn upwardly against the fuse to the position 9'. The hook 8 being connected to hook 9 by link 10 is drawn upwardly 100 against the fuse to the position 8', thus holding the fuse securely against the block 1. When the handle 5 is withdrawn to the position 5', the screw 25 has reached the limit of its movement, and the handle may then be turned so that the screw 25 will pass into 105 the portion 21 of the slot 20, and thus lock the hooks in engagement with fuse. The operator may then readily remove the fuse from the transformer.

While the swing of hooks 8 and 9 is fixed, 110 they may be adjusted to engage a smaller fuse by means of the screw 18. By turning

this screw farther into the sleeve 16, when the parts are in the position shown by the solid lines in Fig. 1, the hooks 8 and 9 will be moved toward the block 1, so that in their initial position they will be substantially as shown at 8' and 9' and, when the handle 5 is pulled from the tube they will be drawn much nearer the bottom of block 1, so that they will engage a smaller fuse.

10 While I have shown my device in its preferred form it is obvious that many changes may be made within the scope of the appended claims without departing from the spirit of my invention. It is therefore to be understood that I am not limited to the precise details illustrated or described, and that the words which I have used in describing my invention are words of description and not of limitation.

20 What I claim is—

1. A fuse handling device comprising a handle, a block thereon, a hook pivotally connected to said block, means coacting with the handle for moving the hook toward the block, and adjustable means for limiting the throw of said hook.

2. A fuse handling device comprising a handle, a block thereon, a hook pivotally connected to said block, means comprising a part of said handle for swinging the hook

toward said block, and means for positively adjusting the movement of said hook.

3. A fuse handling device comprising a handle, a plurality of fuse-engaging hooks pivotally connected to said handle, means for swinging said hooks toward said handle, means for adjusting the swing of said hooks, and means for locking said hooks at the extremity of the swing.

4. A fuse handling device comprising a block, a tubular handle associated with said block, hooks pivotally connected to said block and to each other in spaced parallelism, means within said handle and operatively connected to one of said hooks for throwing the same toward or from said block, and means associated with the last-mentioned means for varying the throw of said hooks from said block.

5. A fuse handling device comprising a block, a tubular member on said block, a member slidably mounted within said tubular member and operatively connected with a plurality of hooks on said block; said hooks being pivotally connected to swing in parallelism toward said block when said second-mentioned member is withdrawn from said tubular member.

HARLAN S. ROBINSON.
